ATTORNEY.

UNITED STATES PATENT OFFICE

2,227,479

HANDLE FOR DRAWERS

Philip Zalkind, New York, N. Y.

Application December 3, 1935, Serial No. 52,731, which is a division of Serial No. 692,937, October 10, 1933, which in turn is a division of Serial No. 631,682, September 3, 1932. Again divided and this application August 27, 1938, Serial No. 227,091

4 Claims. (Cl. 229—52)

My invention relates to containers and casings therefor and more specifically relates to drawers adapted to be pushed into and pulled from a casing made of suitable sheet material.

5 My invention is a division of Ser. No. 52,731, filed December 3, 1935, a division of Ser. No. 692,937, filed October 10, 1933, which in turn is a division of Ser. No. 631,682, filed September 3, 1932.

10 In general, my invention embodies a container and casing combination made of sheet material such as cardboard or paper box board, corrugated board, fibre board and/or any other material adaptable or adapted to be stamped and bent upon creased, scored, or otherwise formed and predetermined lines for the purposes hereinafter described after the same has been suitably cut, creased, stamped or blanked out in outline form.

15 Drawers of the type described above must be sufficiently rugged to withstand the strains to which they are subjected in being pushed into and pulled from a casing. To justify their construction from sheet material of the type described above, they must be of low cost and be adapted for shipment in a collapsed state.

20 Accordingly, objects of my invention are: to provide means for making inexpensive and yet rugged containers of sheet material; to make containers adapted for shipment in a "knocked-down" condition and arranged to be simply and easily assembled and erected by the user; and to make containers which in "knocked-down" or collapsed condition lie substantially flat, so as to occupy a minimum of space for shipping and 25 storage.

25 In order to readily push and pull a drawer into and from a casing, it must obviously be provided with a handle. I have discovered a special formation for the handle which not only insures 30 a secure support therefore, but also does not interfere with the packing of the collapsed containers for shipment.

35 Accordingly, further objects of my invention are to provide a handle secured to an integral extension of the front wall bent on a scored line to lie behind the front wall; and a handle mounted on a separate reinforced sheet of material adapted to be placed in face to face relation with the front wall of a collapsible container 40 made of sheet material suitably scored to be assembled into the form of the container.

45 In pushing and pulling the drawer from its casing, it is subjected to shearing strains along the vertical edges of the front wall. I have discovered that by transferring these strains to the

side walls, they can be distributed over a larger area and are therefore less likely to be destructive of the container.

5 Accordingly, still further objects of my invention are to provide means in a casing for transferring the shear along the vertical edges of the container to the side walls; bracket arrangements for connecting the front and side walls; and tongues integral with the front wall and suitably secured to the side walls, as by extending the 10 tongues between an outer and inner integral side wall.

15 Other objects of my invention will be apparent from the following description taken together with the drawing in which

20 Figure 1 shows a blank or development made from a sheet of material adapted to be formed into a container or file drawer in which the front, back, and side walls are formed of a plurality of thicknesses of material and which without the use of fasteners, is provided with a handle produced by bending the sheet material upon a score line.

25 Figure 2 is a perspective view of a drawer formed from the blank shown in Figure 1.

30 Figure 3 is a fragmentary sectional view on the plane 3—3 of Figure 2, showing the form of construction for the front wall and handle or pull of the drawer.

35 Figure 4 is a view in perspective of a wall piece having a tab adapted to serve as means for pulling the drawer open.

40 Figure 5 is a fragmentary sectional view similar to Figure 3, except that a wall piece as shown in Figure 4 is incorporated in the front wall.

45 Referring now to Figure 1, it will be seen that I illustrate one type of drawer or container blank formed as by cutting, scoring or stamping from suitable sheet material, such as corrugated board, container board, box board, and the like. The blank consists of a bottom 15, a front wall 16, rear wall 17, a front wall extension 18, a rear wall extension 19, side walls 20, side wall extensions 21, front wall tongues 22, rear wall tongues 23, auxiliary front and rear wall tongues 24, and 50 25 formed by the blank outlined and scores 26, 27, 28, 29, 30, 31, 32 and 33.

55 It will be noted that the score line 31 between the bottom 15 and the front 16 does not extend across the entire blank but is discontinuous in the center of the blank, the two halves being connected by the slots 1, 2 and 3 extending through the blank and outlining the tab 4. As is clearly shown in Figures 2 and 3, the tab 4 will lie in the plane of the bottom member 55

15 and project beyond the front 16 of the drawer leaving the slot 5 in the drawer front, backed up by the front wall extension 18 when the auxiliary wall 18 and the tongues 24 connected thereto are folded about scores 30 and caused to line on the wall 16 and tongues 22, and when the front wall 16 is folded at right angles to bottom member 15.

It will be understood that the front and rear 10 wall extension and tongues 18, 19, 24 and 25 may be adhesively secured, respectively, to the portion 16, 17, 22 and 23. Rectangular portions 42 are cut out of the auxiliary front wall 18 and will occupy a position shown on wall 16 when 15 folded as described. Rectangular portions 43 are cut out of the wall 19 and when said wall and tongues 25 are folded upon the scores 33, said portions will occupy a position on the wall 17. Tabs 44 and 45 cut from the tongues 22 and 20 23, are formed on the side wall extension 21 respectively. The tabs 44 and 45 are adapted to fit into the corresponding openings 42 and 43 respectively, when the container is set up in order to securely hold the parts thereof in position. 25 Similarly, tabs 46 and 47 formed at the ends of the side wall extension 21 are adapted to fit in the openings 42 and 43 at the other side of the blank. The tabs 44 and 46 may be made of a distinctive shape and the openings 42 similarly shaped to serve as an aid in indicating to the consumer the manner in which the blank is to be folded and assembled. Also the tabs 45, 47 and notches 43 may be given still another shape for a similar purpose. Near the ends of 30 each of the tongues, ears 48 are formed which are adapted to be juxtaposed in pairs, and enter perforations 49 or 50 in the scores 28 and 35 29, respectively, when the container is folded.

In Figure 2 I show a perspective view of a 40 drawer formed from a blank, like that shown in Figure 1, and the manner in which the side wall extension 21 is folded into the drawer to lock the lugs 48 in position. This view also shows the manner in which the side wall extension is locked in position by the tab 45 in the opening 45 43 formed in the rear wall extension 19. It will be understood that the corresponding parts at each corner of the drawer are similarly assembled and that when the drawer is finally set up, the surface of the tab 45 and rear wall extension 50 19 lie in the same place, making a smooth interior surface for the drawer. This view also shows the manner in which the tab 4 extends in front of the drawer to act as a handle for pulling the drawer from a casing.

Figure 3 shows a section of the front wall having a tab 4 cut from front wall 18 along the lines 1, 2 and 3 in Figure 1 and caused to project from the container in the plane of the bottom 55 15 when the front wall 18 is bent normal thereto. This construction is less costly than that of providing a separate handle.

It will be noted that by making the slits 1 and 2 relatively short, that is of the order of the 60 thickness of the sheet material, the slot 5 thus produced is of the same order of thickness as the material and thus provides an opening through which a tab may be inserted from the rear of the front wall 18. Such a tab will extend through the slot and be accessible from the 65 front of the drawer. This construction will now be described in further detail.

In Figure 5, I show the tab or drawer pull construction used in a three-ply front wall. In 70 this case the slot 5 is formed in the blank through 75

which a tab 7, formed on an auxiliary wall piece 6, see Figure 4, may project. The tab 7 is formed from the material of face 11 of the wall piece 6, leaving the opening 8 in the face 11. The tab 7 is adapted to lie in the same plane as a flange 5 10 10 also formed on the bottom of the piece 6. Figure 5 shows the opening 8 formed when the tab 7 is turned outwardly and also shows the position occupied by the tab 7 and flange 10 above described. It will be understood that the 10 flange 10 may be secured adhesively or otherwise to the bottom 15 of the box. Moreover, it will be understood that the front wall extension 18 may be somewhat shorter than the front wall 16 in order to provide the space 9 between the 15 bottom edge of the front wall extension 18 and the bottom 15 to accommodate the flange 10.

It is obvious that many modifications may be made in my invention within the scope and meaning of the appended claims, and I do not 20 limit my invention to the particular form described, which is shown by way of illustration only. Now having described my invention in a manner that it may be readily understood by one skilled in the art, 25

I claim:

1. In a container, a front wall; side walls; and a bottom wall; said front wall comprising an inner and outer face; said outer face being an integral extension from said bottom wall; said 30 inner face being an integral extension from said outer face; a slot cut from said outer face beginning at the junction between said outer face and said bottom wall and extending partly up the height of said outer face; and a handle comprising a tab lying in a plane parallel to said bottom wall and protruding through the slot in said outer face; said tab being formed in a pad having one portion enveloped by said inner and outer face of said front wall. 40

2. In a container, a front wall; side walls; and a bottom wall; said front wall comprising an inner and outer face; said outer face being an integral extension from said bottom wall; said inner face being an integral extension from said 45 outer face; a slot cut from said outer face beginning at the junction between said outer face and said bottom wall and extending partly up the height of said outer face; a handle comprising a tab lying in a plane parallel to said bottom 50 wall and protruding through the slot in said outer face; and an angular pad having one portion enveloped by said inner and outer face of said front wall, and another portion lying in contact with said bottom wall; said handle being integral 55 with that portion of the pad in contact with said bottom wall, and being formed from material cut from that portion of the pad lying between the inner and outer face of the front wall. 60

3. In a container, a front wall, side walls; and a bottom wall, said front wall comprising an inner and outer face; said outer face being an integral extension from said bottom wall; said inner face being an integral extension from said 65 outer face; a slot cut from said outer face beginning at the junction between said outer face and said bottom wall and extending partly up the height of said outer face; a handle comprising a tab lying in a plane parallel to said bottom 70 wall and protruding through the slot in said outer face; and an angular pad having one portion enveloped by said inner and outer face of said front wall, and another portion lying in contact with said bottom wall, the lower edge 75

of said inner face engaging said last named portion; said handle being integral with said pad.

4. A handle member for a container; said container having a bottom wall; an end wall; and a slot in said end wall; said handle member comprising an angular pad having a portion adapted to engage the bottom wall and a portion

adapted to engage the end wall; a tab integral with said bottom wall portion of said pad and being formed from material cut from the end wall portion of the pad; said tab being adapted to extend through said slot of said end wall when the handle member is mounted in place. 5

PHILIP ZALKIND.
